UNITED STATES PATENT OFFICE.

FREDERICK ROW PARKS, OF FULTON, NEW YORK.

AUTOMATIC POULTRY-FEEDER.

1,192,677.

Specification of Letters Patent. Patented July 25, 1916.

Application filed February 18, 1916. Serial No. 79,128.

To all whom it may concern:

Be it known that I, FREDERICK R. PARKS, a citizen of the United States, residing at Fulton, in the county of Oswego and State 5 of New York, have invented certain new and useful Improvements in Automatic Poultry-Feeders; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in automatic feeders for poultry, animals, etc., and consists in the provision of means whereby gates or dampers 20 may be actuated to allow feed to be discharged at different hours, regulated by clockwork.

My invention comprises various details of construction, combinations and arrangements of parts which will be hereinafter 25 fully described, shown in the accompanying drawings and then specifically defined in the appended claims.

I illustrate my invention in the accompanying drawings, in which:

Figure 1 is a front elevation of my automatic grain feeding apparatus, partly in section. Fig. 2 is an end elevation. Fig. 3 is a sectional view taken on line 3—3 of 35 Fig. 2. Fig. 4 is a section on line 4—4 of Fig. 3.

Reference now being had to the details of the drawings by letter, A designates a hopper, adapted to be supported in any suitable 40 manner as by suspension wherever the apparatus is to be used and having a series of metallic partitions B which are angled at B' and forming means for spacing the same and which are held in slots in the contracted 45 portion of the hopper. The hopper is provided with adjustable inclined partitions C which may be regulated to cause the feed to be deposited in various compartments formed by the partitions, so that quantities 50 of material may be fed at different hours. The bottom of the hopper has openings D, one for each compartment, and E is a rock shaft having gates or doors F pivoted at their inner ends thereto and their outer ends 55 F' are free and project beyond the bottom of the hopper, and each has a lug F² struck

up therefrom, forming trips. Fastened to the lower portion of the hopper is a bar H secured to the hopper frame. A series of horizontally disposed tilting levers I are 60 pivotally mounted upon the pins I' and the long arms of said levers are adapted to engage underneath the free ends F' of the doors and support the same in closed relation with the openings in the bottom of the 65 hopper. A longitudinal bar L has pins L' projecting therefrom and positioned between the short arms of the levers and adapted, when actuated in one direction, to cause the levers to tilt upon their pivots. 70

Bracket bars N are secured to the ends of the hopper and support the pulleys O and O', mounted near the ends of the hopper and over which a line Q passes which has a weight R fastened at one end, the other end 75 passing about a pulley J having a clutch collar J² rotating therewith, which latter and the pulley are journaled upon a stationary shaft J³ held by a bracket member J⁴ upon the end of the hopper. A second pulley, 80 designated by letter J⁵, is loosely journaled upon said rod and has a clutch collar J⁶ integral therewith adapted to be held in engagement with the teeth of the clutch collar J² by means of a coiled spring S which bears 85

between the pulley J⁵ and the bracket arm J⁴. A belt J⁷ passes about the pulley J⁵ and also a pulley J⁹ upon the shaft J¹⁰ of the hour hand of a clock J¹¹ and affording means whereby a movement may be imparted to the 90 line Q at predetermined moment for the purpose of actuating one or another of the levers to allow certain compartments to discharge their contents. A trip, designated by letter T, is loosely mounted upon the line Q 95 and is adapted to be moved into contact successively with the short arms of the several levers by the lug Z which is fixed to the line Q and when the latter is moved in one direction by the pulling of the weight R thereon. As the trips contact with the various levers, they will be tilted upon their pivots, allowing the doors to swing down to allow the contents of the compartments to fall 100 therefrom. The line Q has an adjustable lug Z adapted to contact with the trip T. 105

A spreading apparatus W, inverted V-shaped in cross section, is suspended a suitable distance below the bottom of the hopper and serves as a means for spreading the 110 food as it falls from the hopper.

The device for resetting the doors consists

of the swinging bail-shaped member X pivoted at its ends at X' to the ends of the hopper and, when swung in one direction, will throw the doors to their horizontal positions where they will be engaged and held in such position by the long arms of said levers.

The parts of the apparatus being arranged as shown, food is placed within the compartments, the various inclined partitions C being adjusted to cause the food to fall by gravity into different compartments. As the clock mechanism releases the pulley 10, the weight which is fastened to the end of the line Q will cause the pulleys J⁵ and J to rotate, unwinding the line and, when the lug Z comes in contact with the trip T, it will move the latter frictionally against the outer short arm of the lever I and cause the lever to swing horizontally, throwing the inner 10 end of the lever from engagement with the projecting end of the door F' and which, when released, will fall by gravity and, when the rope is allowed to make another intermittent movement at a predetermined movement, determined by the setting of the clock mechanism, the lug Z will push the trip T against the next lever and so on in succession, swinging the same in order and allowing the different compartments to deposit 25 their contents upon the spreader below. When it is desired to return the parts to their normal position, the operator, by swinging the bail-shaped member X, may throw the doors back to horizontal positions 30 and, by turning the pulley J, the line or rope may be rewound upon the same and, by giving a longitudinal movement to the bar L to the right, the pins thereon coming in contact with the various short arms of the 35 levers will throw the same back to their normal positions underneath the projecting ends of the doors, the said levers being stopped by the lugs F². After the parts are reset in the manner shown, the weight upon the levers 40 will hold the same in their set positions and the bar L may be moved back to the left so that the pins L' thereon will be out of the 45

paths of the short arms of the levers when again tilted.

By the provision of an apparatus embodying the features of my invention, it will be noted that the food may be directed to different compartments where it may be desired to have the same automatically dumped at predetermined moment by setting the clock to have a door actuated at any particular hour.

What I claim to be new is:—

1. An automatic poultry and animal feeding apparatus comprising a hopper with partitions therein and having openings in the bottom thereof, a series of separate and pivotal doors regulating the openings, horizontally disposed pivotal levers for supporting the free ends of the doors, a weighted rope and pulley about which the same winds, clock mechanism for releasing the rope, a movable trip upon the rope and a link fixed to the latter adapted to move the trip successively against the corresponding ends of 70 said levers to release the same from said doors, and means for limiting the movements of the levers in one direction.

2. An automatic poultry and animal feeding apparatus comprising a hopper with partitions therein and having openings in the bottom thereof, a series of separate and pivotal doors regulating the openings, horizontally disposed pivotal levers for supporting the free ends of the doors, a weighted 80 rope and pulley about which the same winds, clock mechanism for releasing the rope, and a movable trip upon the rope and a link fixed to the latter adapted to move the trip successively against the corresponding ends 85 of said levers to release the same from said doors.

In testimony whereof I hereunto affix my signature in presence of two witnesses.

FREDERICK ROW PARKS.
